UNITED STATES PATENT OFFICE

CHARLES E. CONSTABLE, OF CINCINNATI, OHIO, ASSIGNOR TO THE NATIONAL MARKING MACHINE COMPANY, OF CINCINNATI, OHIO, A CORPORATION OF OHIO

TRUCK LIFT

Application filed October 7, 1929. Serial No. 392,064.

The object of my invention is to provide a truck lift of simple, durable and inexpensive construction, especially adapted to elevate trucks such as used for handling laundry from one floor to another, and to provide means whereby trucks placed on the lift will be automatically delivered to the receiving track provided for that purpose, and will be automatically operated to a second position after the truck has been delivered, after which the trucks are automatically returned to the lift and lowered to the first floor.

More specifically it is the object of my invention to provide a lift shaft having a movable cage adapted to move upwardly and downwardly in said shaft by means of the ordinary electrically controlled operating mechanism; and to provide in connection with the elevating and lowering mechanism improved means whereby the elevating and lowering movements of the lift will be automatically controlled by the movement of the lift and by the movement of the trucks as they are moved into and out of position thereon.

A further object is to provide a lift shaft having a cage adapted to be moved upwardly and downwardly therein by means of suitable electrically operated and controlled mechanism, and a gate for the lower shaft opening having means for automatically setting into operation the lift mechanism upon the closing of said gate.

A further object is to provide in a lift shaft having a cage adapted to move upwardly and downwardly therein an improved tilting platform for said cage whereby trucks carried by said cage may be automatically delivered from or received in said cage.

My invention consists in the construction, arrangement and combination of the various parts of the device, whereby the objects contemplated are attained, as hereinafter more fully set forth, pointed out in my claims, and illustrated in the accompanying drawings, in which:

Figure 1 is a vertical sectional view of the upper end of a lift shaft having a movable cage mounted therein showing the cage at its upper limit of movement; and

Figure 2 is a vertical sectional view of the lower end of the shaft showing the cage at its lower limit of movement and the manner in which the truck is supported thereon.

Figure 3 is an enlarged detail sectional view taken on the line 3—3 of Figure 1.

Figure 4 is a diagrammatical plan view of the cage and the truck supporting tracks, showing the arrangement of the tracks whereby a truck may be moved outwardly through an opening near the upper end of the shaft, and another truck moved inwardly through an opening below the first said opening.

Figure 5 is a diagrammatical view showing the wiring of that portion of the controlling circuits involved in my improvement.

Figure 6 is a detail view of one of the switch devices used in my improved lift.

Figure 7 is a detail view of one of the switch operating devices used in connection with the switch illustrated in Figure 6, the switch being illustrated by dotted lines.

Figure 8 is a plan view of the switch and the mechanism actuated by the gate for actuating the switch as illustrated in Figure 6.

Figure 9 shows another form of switch device used in my improved mechanism for operating the same.

Figure 10 is a front elevation of one of the snap switches.

Figure 11 is a detail sectional view taken on the line 11—11 of Figure 3.

Figure 12 is a detail view illustrating the inner end of the trip bar and the manner in which it is engaged by an actuating lug on the cage.

The numeral 10 indicates the lift shaft which comprises upright frame members 11 and horizontal frame members 12. The usual brace members 13 are provided. The side members of the shaft are provided with vertical guides 14 in the form of T-irons, the flanges of said irons being riveted to the members 12 and 13 of the sides. The front of the shaft is provided with an upper opening 15, a lower opening 16 and an intermediate opening 17, said openings being for the pur-

pose of permitting trucks 18 to be moved into and out of the shaft.

The shaft 10 is provided with a cage 19 having a suitable frame provided with angle irons 20 designed to co-operate with the upright guides 14, so that the cage is free to move upwardly in the shaft. The cage is elevated and lowered by electrically controlled mechanism not illustrated and which

10 forms no part of my present invention.

The said electrically controlled elevating and lowering mechanism is provided with what I shall term descending and ascending circuits. The closing of the 15 ascending circuit causes the cage to be elevated and the opening of said circuit causes the cage to stop and to be retained in the position it assumes at the time the circuit is opened. The closing of the descending circuit causes the locking mechanism of the 20 cage to be released and the cage lowered. The opening of the descending circuit causes the cage to be stopped and retained in the position it assumes when the circuit is opened.

25 The bottom of the cage 19 is provided with a platform 21 pivotally mounted by means of a shaft 22 supported horizontally in said cage, so that the front and rear edges of the cage may be elevated and lowered for the 30 purpose hereinafter made clear. The side edges of the platform 21 are provided with bracket members 23, each of which projects downwardly from the bottom of the cage and is provided with laterally extending 35 shafts 24. Each of the shafts 24 has a roller 25 designed to operate in suitable guides 26 secured to the sides of the shaft. Each of the guides 26 is provided with a curved portion 27 near its upper end, so arranged that 40 as the cage 19 is elevated and lowered past the curved portion, the roller 25 will be moved rearwardly, causing the platform 21 to be oscillated on the pivot 22 and its front edge to be lowered, while its rear edge is elevated. The platform normally assumes an 45 inclined position as illustrated in Figure 2 with its rear edge lower than the front edge.

Adjacent to the bottom of the opening 15 I have provided what I shall term an outgoing truck track 28, and adjacent to the bottom of the opening 17 I have provided what I shall term an incoming truck track 29, and at the bottom of the opening 16 an incoming and outgoing track 30. The bottom 50 of the cage is provided with a cage track 31 adapted to align with any of the other tracks when the cage is in certain positions of its movement, so that the trucks may be moved onto and from the cage when the cage 55 is at its lower limit of movement, and may be moved from the track 31 to the track 28 when the cage is at its upper limit of movement, and from the track 29 to the track 31 when the cage is at what I shall term an intermediate position of its movement.

The tracks 28 and 29 are supported by the floor above the main floor. The track 29 is inclined downwardly and beneath the track 28. The track 28 is provided with a curved portion 32 so that the outer ends of the tracks 70 28 and 29 may be supported side by side. Said tracks are provided with means whereby trucks may be transferred from one track to another.

The inner and inclined portion of the track 29 is provided with a pivoted trip mechanism 33 having an upwardly extending lug 34 designed to be engaged by a downwardly extending flange 35 on the bottom of the trucks 18. The said lug 34 retains the truck against inward movement on the inclined track. The outer end of the lever 33 is provided with a weight 36, whereby the inner end of the lever will be normally retained in an elevated position. A lug 37 limits the downward movement of the member 36, and in turn the upward movement of the forward end of the lever 33.

The forward end of the lever 33 is provided with a pivoted dog 38 having a lug 39. The parts are so arranged that the free end of the dog 38 may be swung upwardly and locked against downward movement by the lug 39. The free end of the lug 38 is designed to rest in the path of a lug 40 carried by the cage 19, whereby downward movement of the cage will cause the lug 40 to engage the lug 38 and cause the forward end of the lever 33 to be lowered and the lug 34 to disengage the flange 35, permitting the truck 18, as shown by dotted lines, to be released and to be moved inwardly on the platform 21.

As soon as the lug 40 has passed the lug 38, the free end of the lever 33 is then permitted to be elevated with the lug 34 in the path of the flange 35 of the next incoming truck. It should be understood that a number of trucks are supported on the track 29, all of which are free to move inwardly by gravity upon the inward movement of the truck adjacent to the shaft.

It will be seen that the lug 40 may be moved upwardly past the lug 38 without actuating the lever 33, and that the trucks will not be released only as the cage is moved downwardly.

It will readily be seen from the foregoing description that trucks on the platform 31 may be automatically delivered to the track 28 as the cage reaches its upper limit of movement, due to the action of the roller 25 in the curved portion 27 of the guides 26. Thus mechanically operated means is provided whereby trucks may be automatically delivered and received when the cage is in the upper end of the shaft. The trucks are manually placed in the cage when at its lower limit of movement.

As before stated, the elevating and lowering mechanism may be any one of a num-

ber of hoisting mechanisms now in commercial use, and is provided with suitable electrically controlled mechanism for operating the same, which includes the descending and 5 ascending circuits.

In the diagram illustrated in Figure 5 I have provided a current generator 41 having conductors 42 and 43 which include the mechanism for controlling the upward movement of the cage. Said conductor 43 also includes a snap switch 44. The descending circuit includes a conductor 45 which terminates in branch conductors 46 and 47 and in snap switch devices 48 and 49. Both of these 10 switches 48 and 49 are connected to a conductor 50, which in turn is connected to the conductor 42. The conductor 45 is connected to the conductor 43 so that the ascending and descending circuits are in parallel from 15 a common generator.

In Figure 10 I have illustrated one form 20 of a snap switch 51 now in common use, and in which is included push buttons 52 and 53, one of the buttons being adapted to be moved inwardly to open the circuits and the other one to close it.

Inasmuch as all three of the switch devices 44, 48 and 49 are the same, the description of one will apply to all. The numeral 52 will be used to indicate the button 25 for closing the circuits and the numeral 53 to indicate the button for opening the circuit.

Secured to the bottom of the cage 19 by 30 means of a suitable bracket 54, I have mounted the switch 44 with the buttons 52 and 53 in a common horizontal plane, said buttons projecting forwardly.

Secured to the forward side of the cage 35 19 I have provided a bracket 55 to which a bell crank lever 56 is pivotally connected. The downwardly extending arm of the bell crank is supported in front of the button 52. The bell crank is provided with a forwardly 40 extending arm 57 designed to be engaged by a lug 58 secured to the gate 59 slidably mounted to close the opening 16 by being moved downwardly.

The lug 58 is so mounted that as the gate 59 is moved downwardly to a closed position, it will engage the lug 57 causing the lower arm of the bell crank 56 to be moved rearwardly and the button 52 moved to closed position. This will cause the ascending circuit 55 to be closed and the cage to be moved upwardly until the platform 21 is in alignment with the track 28. The button 53 of the switch 44 is then designed to engage a cam 60 secured to the cross member 12 of the shaft, 60 which will cause the said button 53 to be moved inwardly and the ascending circuit to be opened. The truck supported on the platform 21 will then be moved toward the track 28 by gravity. As the truck 18 is moved 65 outwardly in position on the track 28, the

lug 35 will engage the trip lever 61 mounted between the rails of the track in the manner illustrated in Figures 1 and 9.

The trip lever 61 is pivotally mounted and has a downwardly extending arm 62 to which 70 a link 63 is connected. The said link 63 is in turn pivotally connected to a shoe 64 pivotally connected to the inner end of one of the track members 28.

The shoe 64 is designed to be moved into 75 the path of the button 52 of the switch 48, which is also secured to the bottom of the cage by means of a suitable bracket 65, so that the descending circuit is closed, which will cause the cage to be moved downwardly until the platform 21 is in alignment with the track 28, at which time the button 53 of the switch 48 will engage a cam 66 carried by the shaft 10, causing the cage to stop in the last said position.

The arm 62 is provided with a spring 67 for moving the shoe 64 inwardly out of the path of the button 52 of the switch 48 as the said switch is moved upwardly.

Secured to the platform 21 is the switch 49 80 by means of a suitable bracket 68. The switch is mounted with the buttons 52 and 53 projecting upwardly. A bracket 69 is also provided in which is pivotally mounted a bell crank lever 70. One arm of the lever 70 is designed to rest upon the upper end of the push button 52, while the other arm of the lever projects upwardly and is designed to be engaged by the flange 35 of the truck 18 as said trucks are moved to position on the 85 platform 21, and when so engaged will cause the button 52 to be moved to a closed position, which will then start the cage downwardly.

A rock shaft 71 is also pivotally mounted 90 on the platform 21 by a suitable bearing 72. The inner end of the rock shaft 71 is provided with a rock arm 73 having its free end designed to rest normally above the button 53. The outer end of the shaft 71 is provided with a rock arm 74, the free end of which is designed to engage a lug 75 near the bottom of the shaft 10 as the cage is moved downwardly to its lower limit of movement, whereby the shaft 71 will be rocked and the button 53 moved to position to open the switch 49, thereby causing the downward movement of the cage to be stopped with the platform 21 in alignment with the track 30 and with the arm 57 of the bell crank 56 in 100 position above the flange 58 of the gate 59. The gate 59 may then be moved to an open position and locked in said position by suitable locking mechanism not illustrated.

The truck may then be removed from the 105 platform 21 and another truck placed in position thereon, after which the gate 59 may be lowered, causing the ascending circuit to be closed in the manner above described.

Thus it will be seen that I have provided 110

a lift having movable cage provided with a tiltable platform and provided in connection therewith means whereby the up and down movement of the cage will cause the platform to be tilted from one inclined position to another, whereby trucks on said platform may be automatically received and delivered. The platform is provided with a simple and durable means for performing its tilting operation.

The curved portion of the guide for tilting the platform may be such that the platform may be swung easily from one position to another, thereby eliminating sudden jars and strains.

It will further be seen that I have provided electrical means whereby the elevating and lowering of the cage may be automatically controlled by the movement of the cage, and by the movement of the trucks into and out of said cage, and provided in connection therewith safety means whereby the automatic elevating and lowering mechanism cannot be set into operation until the gate 59 has been closed.

Thus it will be seen that I have provided a lift in which a minimum amount of labor is required to elevate and lower trucks from the lower floor to the upper floors of a building.

I claim as my invention:

1. In combination, a shaft, a cage mounted to move upwardly and downwardly in said shaft, a truck track in said cage, exterior upper and lower tracks for supporting outgoing trucks, an exterior intermediate track for supporting incoming trucks, said tracks being mounted one above the other, trucks for said tracks, means actuated by the movement of said cage for automatically delivering trucks from said cage track to one of said outgoing tracks as the cage track is moved to position in alinement with the outgoing track, and means actuated by return movement of said cage for automatically delivering trucks from said incoming tracks to the cage track as the cage track is brought into alinement with said incoming track.

2. In combination, a shaft, a cage mounted to move upwardly and downwardly in said shaft, a truck track in said cage, an exterior track for supporting outgoing trucks, an exterior intermediate track for supporting incoming trucks, said tracks being mounted one above the other, trucks for said tracks, means actuated by the movement of said cage for automatically delivering trucks from said cage track to one of said outgoing tracks as the cage track is moved to position in alinement with the outgoing track, means actuated by return movement of said cage for automatically delivering trucks from said incoming tracks to the cage track as the cage track is brought into alinement with said incoming track, and electrical means actuated by

the up and down movement of said cage and by the movement of said trucks into and out of said cage for automatically controlling the movement of said cage.

3. In combination, a shaft, a cage mounted to move upwardly and downwardly in said shaft, a truck track in said cage, exterior upper and lower tracks for supporting outgoing trucks, an exterior intermediate track for supporting incoming trucks, the last track being supported adjacent to the upper track, the inner end of the incoming track being curved downwardly and inwardly beneath the upper track, trucks for said tracks, means actuated by the movement of said cage for automatically delivering trucks from said cage track to said outgoing tracks as the cage track is moved to position in alinement with the outgoing track, and means actuated by return movement of said cage for automatically delivering trucks from said incoming tracks to the cage track as the cage track is brought into alinement with said incoming track.

4. In combination, a shaft, a cage mounted to move upwardly and downwardly in said shaft, a truck track in said cage, an exterior track for supporting outgoing trucks, an exterior intermediate track for supporting incoming trucks, said tracks being supported adjacent to each other, the inner end of the incoming track being curved downwardly and inwardly beneath the outgoing track, trucks for said tracks, means actuated by the movement of said cage for automatically delivering trucks from said cage track to said outgoing tracks as the cage track is moved to position in alinement with the outgoing track, means actuated by return movement of said cage for automatically delivering trucks from said incoming tracks to the cage track as the cage track is brought into alinement with said incoming track, and electrical means actuated by the up and down movement of said cage and by the movement of said trucks into and out of said cage for automatically controlling the movement of said cage.

5. In combination, a shaft, a cage mounted to move up and down in said shaft, an outgoing track, an incoming track, the outer ends of said tracks being side by side and substantially at the same level, the inner end of the incoming track being below the inner end of the first track, whereby trucks carried by said cage may be delivered to the outgoing track and other trucks carried by the incoming track delivered to said cage when the cage is at position in alinement with said tracks.

6. In combination, a shaft, an outgoing track, an incoming track, the outer ends of said tracks being side by side and substantially at the same level, the inner end of the

incoming track being below the inner end of the first said track whereby trucks carried by said cage may be delivered to one of said tracks, and trucks carried by the other track ⁵ may be delivered to said cage when the cage is opposite the respective tracks.
